UNITED STATES PATENT OFFICE.

GEORGE HENRY WHEARY, OF RACINE, WISCONSIN.

DESIGN FOR A DOWEL BOLT FOR TRUNK OR SIMILAR ARTICLE.

Application filed January 26, 1923. Serial No. 4,997. Term of patent 7 years.

To all whom it may concern:

Be it known that I, GEORGE HENRY WHEARY, a citizen of the United States, residing at Racine, in the county of Racine and State of Wisconsin, have invented new, original, and ornamental Design for Dowel Bolt for Trunk or Similar Article, of which the following is a specification, reference being had to the accompanying drawing, forming part thereof.

Figure 1 is a perspective view of a dowel embodying my new design.

Figure 2 is a plan view of the device shown in Fig. 1.

I claim:

The ornamental design for a dowel bolt for trunk or similar article, as disclosed herein.

GEORGE HENRY WHEARY.
